UNITED STATES PATENT OFFICE.

SIMON E. SCHROEDER, OF OAK PARK, ILLINOIS.

WRINGER.

Application filed March 24, 1923. Serial No. 546,307.

My invention relates to clothes wringers and has reference particularly to the mechanism whereby the upper roll is mounted in position and held at a tension against the lower roll.

The principal objects of my invention are to provide improved means for clamping the upper roll in place; to permit independent removal of the upper roll from the wringer frame when the clamping means is released; to afford a release which is so prominent and extensive and easy to operate that release of the pressure between the rolls is assured in an emergency and the safety of the wringer greatly increased; to hold the upper roll in place by means of a frame which swings transversely of the rolls; to provide an improved drain-board construction wherein the drain-board is readily shifted to opposite positions; and in general, to provide an improved wringer construction of simple form and light weight, which is economical to manufacture and conveniently assembled.

On the drawings:

Fig. 1 is a side view of a wringer embodying my improvements;

Fig. 2 a longitudinal vertical sectional view of the wringer;

Fig. 3 a sectional view taken on the line 3-3 of Fig. 2;

Fig. 4 a transverse sectional view taken on the line 4-4 of Fig. 1;

Fig. 5 a transverse sectional view taken on the line 5-5 of Fig. 1;

Fig. 6 a similar sectional view showing the swinging frame in the released position;

Fig. 7 a sectional view on the line 7-7 of Fig. 1, showing the swinging frame in the released position;

Fig. 8 a detail sectional view on the line 8-8 of Fig. 1;

Fig. 9 a view similar to Fig. 5, showing a modified form of bearings for the upper roll and mechanism co-operating therewith for holding the roll in place; and

Fig. 10 a side view of a wringer partly in section showing a modified form of construction.

Referring to the drawings, the numerals 1 and 2 indicate the end castings of the main frame which are oppositely arranged and connected together by tie rods 3 at each side of the wringer, said rods being passed through apertures in laterally projecting

bosses 4 of the end castings 1 and 2, and secured in place by nuts 5 which are threaded on the rods. The end castings 1 and 2 are of similar construction, each comprising a semi-circular flange 6 with bearing portions 69 7 extending upwardly from the opposite end thereof, as shown particularly in Figs. 5 and 6, and reinforced and connected by webs 8 and 8' to the bosses 4. Extending outwardly from each end casting 1 and 2 are 65 the bosses 9 and 10 respectively which are arranged concentric with the semi-circular flange 6 and turned down externally, as at 11 and 12 respectively, to afford bearings upon which the swinging frame of the 70 wringer is pivoted. The boss 9 of the casting 1 projects outwardly a greater distance than the boss 10 of the casting 2 to afford a connection with a bracket 13, whereby the wringer is supported, and both the bosses 75 9 and 10 are bored out as at 14 and 15 respectively to loosely receive the ends of the shaft 16 of the lower wringer roll 17, said shaft being journaled in bearing blocks 18, preferably of wood, which are supported 80 on the semi-circular flange 6 of the respective end casting 1 and 2 between the flanges 7 thereof.

The upper wringer roll which is indicated at 19 is fixed on the shaft 20, which has the ends journaled in bearing blocks 21, which latter are retained on the shaft by riveting over the ends of the shaft as indicated at 22. The bearing blocks 21 slide into the upper ends of the main frame end castings 90 1 and 2 between the flanges 7, and hold the roll 19 in proper position above the lower roll 17, sufficient clearance being provided between the upper and lower bearing blocks 21 and 18 so that the upper roll 19 bears 95 directly upon the lower roll 17, and when the clamping mechanism hereinafter described, which holds the upper roll in place, is released the upper roll 19 together with the bearing blocks 21 may be lifted out and 100 entirely removed from the wringer.

In the preferred construction, there is a gear connection between the rolls 17 and 19 consisting of intermeshing gears 23 and 24 on the shafts 16 and 20 respectively, and to accommodate this gearing a U-shaped housing 25 is mounted by means of boxes 26 on the rods 3 and clamped against the inner face of the main frame casting 1. Cover plates 27 are secured respectively 105 110

against the inner face of the housing 25 and the inner face of the end casting 2, these plates being secured in place by bosses 28 thereon, which are apertured to receive the 5 rods 3, and clamped in place by the nuts 5. Each plate is provided on its inner face with a U-shaped flange 29 which serves as a guard to embrace the ends of the upper and lower wringer rolls and prevent the clothes 10 running out beyond the ends of the latter, and each of these plates also has a slot 30 extending downwardly from the top thereof between the side portions of the flange 29 to admit the shafts of the upper and lower 15 wringer rolls.

If desired the gears 23 and 24 may be omitted as shown in the modified form of Fig. 10, and if so, the housing 25 is also omitted and the cover plate 27 clamped directly against the inner face of the end casting 1 the same as at the opposite end of the wringer.

A spring housing 31 is mounted at each end of the wringer on the bearings 11 and 12 respectively, and each of said housings comprises a bearing loop 32 at the lower end embracing the respective bearings 11 or 12 of the end castings 1 or 2, and having spaced side walls 33 extending upwardly 20 and connected together at their upper ends by a top wall 34. A bar 35 extends between and is connected to the upper ends of the spring housings 31 to form, with the latter, a swinging frame for releasably holding the upper roll 19 in place, said bar being preferably formed of sheet metal stamped in semi-circular cross section and with flattened ends which are secured to the top walls 34 of the spring housings 31 by 25 cap screws 36. The side walls 33 of each spring housing have inturned flanges 37 extending along the inner edges thereof and serving as guides for a sliding plate 38 which has offset portions 39 and 40 at the opposite ends respectively thereof and upon opposite sides of the flanges 37. The portion 40 at the lower end of the plate 38 forms a seat for the lower end of a compression spring 41 which is held in place on the seat by a projection 42 on the latter which fits into the lower end of the spring 41. A plug 43 is inserted into the upper end of the spring 41 and has a annular flange 44 bearing against the upper end of the spring, 30 and this plug has a recess 45 arranged centrally in the top which is engaged by the lower end of the adjusting screw 46 which is threaded through the top wall 34 of the spring housing. The portion 39 at the upper end of the sliding plate 38 is arranged to project inwardly over the top of the adjoining end casting 1 or 2 of the main frame, and has a slot therein within which a roller 47 is mounted on a pin 48 so as to roll up. 35 onto the top of the bearing block 21 as the

swinging frame is swung to the upright position, and thereby apply the tension of the springs 41 onto the end bearings 21 for resiliently holding the upper roll 19 down against the lower roll 17. The top portion 70 of the loop 32 at the lower end of each spring housing 31 serves as a stop against which the spring seat or projection 40 engages, when the swinging frame is in the released position and holds the sliding plate 75 38 so that the roller 47 on the upper end thereof will clear the top of the end casting 1 or 2, and the faces 49 at the top of the bearing block 21 are curved or inclined to afford the required lift or elevation of 80 the roller 47 as it is moved up onto the bearing block from either side of the wringer, and these faces 49 terminate in a shallow recess or roller seat 50 which is engaged by the roller 47 under spring tension 85 when the swinging frame is in the upright position and releasably holds said frame in the upright position.

The bearing blocks 21 are preferably surrounded by a metal shell 51 to withstand 90 the wear occasioned by the sliding action along the retaining flanges 7 and the operation of the roller on the top face, and said bearing blocks may be similarly constructed with inclined faces and roller seat at the 95 bottom as shown by dotted lines at 52 in Fig. 5, so that said blocks may be reversed to permit excessive wear of the shaft 20 at one side of the bearing opening of the block 21. The lower bearing blocks 18 may 100 also be round if desired, as shown by dotted lines at 53 in Fig. 5 to permit adjustment for the same purpose.

Furthermore, I may employ round bearing blocks 54, as shown in Fig. 9, on the 105 shaft 20 instead of the bearing blocks 21, and in such case the plate 38 is provided with a projection 55 at the upper end with a pair of spaced rollers 56 which straddle the bearing block 54 when the swinging frame 110 is in the upright position and thereby releasably hold the said frame in the upright position.

To limit the swinging movement of the swinging frame the bosses 9 and 10 of the 115 castings 1 and 2 are formed with a thickened portion 57, as shown in Fig. 7, terminating in shoulders 58 which are adapted to be engaged by the lower ends of the side walls 53 of the spring housing 31 when the swinging 120 frame is thrown laterally as far as required.

If it is desired to close the top of the gear housing 25 when the wringer is assembled, a plate 59 shown by dotted line in Fig. 2, may be secured to the bearing 31 and provided with an out-turned portion 60 at the upper end which fits into the upper end of the gear housing 25.

In connection with this wringer, I have also provided an improved drain pan which 130

is more convenient to adjust for draining at opposite sides of the wringer than drain pans which have heretofore been provided. An arm 61 is secured to the lower end of 5 one of the end castings 1 or 2, preferably to the one adjacent the bracket connection 13, and this arm projects inwardly as shown, to a distance somewhat beyond the center of the wringer roll 17. The drain pan 62 10 which is provided with upturned flanges 63 at the opposite ends, is provided with a stamped depression 64 midway between its ends, forming a bearing face 65 which rests flat upon the top of the arm 61 and holds 15 the drain pan at the proper inclination, the drain pan being held on the arm by a bolt 66 which is passed through an aperture in the portion 65 and through an aperture in the arm 61 midway between the ends of 20 the wringer roll, and on the lower end of the bolt I provide a lock washer which is clamped between a pair of plain washers 68 by the nut 69 at a suitable tension to yieldingly hold the drain pan 62 down on the 25 arm 61. At the inner end of the arm 59, there is a pin 70 which projects upwardly, and is adapted to engage in either of the corrugations 71 which are provided adjacent the opposite ends of the drain pan for locking 30 the latter in either of the two positions to which it is adapted to be adjusted. With this construction when it is desired to swing the drain pan around to drain at the opposite side of the wringer, the end of the drain 35 pan adjacent the casting 1 is lifted so as to disengage the corrugation 71 from the pin 70, the resiliency of the spring washer 67 being sufficient to permit the lifting of this end of the drain pan to release same from 40 the pin. The drain pan is then swung around to the reversed position wherein the corrugation 71 at the opposite end of the pan is brought into engagement with the pin 70 and interlocked therewith to hold the 45 drain pan in the newly adjusted position.

From the foregoing it will be observed that the upper roll 19 with its bearings 21 is held in place by the swinging frame comprising the top bar 35 and spring housings 50 31 which may be thrown in either direction to release the upper roll, and as the swinging frame reaches entirely across the top of the wringer and down the sides thereof and may be shifted by pressures applied at any point, 55 it is easy to operate in an emergency and affords greater safety than any wringer heretofore constructed of which I am aware. Furthermore, unlimited separation of the rolls is permitted when the swinging frame 60 is released as the upper roll with its end bearings may be entirely removed from the wringer frame.

While I have shown and described my in-

vention in a preferred form, I am aware that various changes and modifications may be 65 made without departing from the principles of my invention, the scope of which is to be determined by the appended claims.

I claim as my invention:

1. In a wringer, a pair of end bearings, 70 each having a vertical guide channel and an extended bearing boss, a pair of relatively slidable bearings in each channel, rollers journaled in said bearings, a swingable frame supported upon said extended 75 bearing bosses comprising end members, spring pressed slidable plate members associated with said end members, and rollers carried by said plate members and normally bearing upon the upper bearings. 80

2. In a wringer, a lower wringer roll, an upper and relatively movable wringer roll, a swingable spring housing mounted co-axially at each end of the lower roll, 85 a bar connecting said housings, a slideable member supported by each housing, a roller journaled in each member for operative relation with the upper roll and a spring in each housing for urging said slideable members downwardly. 90

3. In a wringer, a supporting frame, bearings secured to the ends of said frame in axial alignment, a roller journaled in said frame coaxial with said bearings, a second frame swingable on said bearings, a second roller positioned normally above the first roller and tension means on said second frame biasing said top roller towards the lower roller when the frame is in normal position. 100

4. In a wringer, a supporting frame, bearings secured to the ends of said frame in axial alignment, a roller journaled in said frame coaxial with said bearings, a second frame swingable on said bearings, a second roller positioned above the first roller, and means for maintaining said swingable frame in operative position and the second roller in yielding engagement with the first named roller. 105

5. In a wringer, a supporting frame, bearings secured to the ends of said frame in axial alignment, a roller journaled in said frame co-axial with said bearings, a second frame including a pair of spring 115 housings swingable on said bearings, tension springs mounted in said housings, a sliding member in each of said housings, having at its lower end means engaged by the lower end of a spring and at its upper end a bearing member, a second roller positioned above the first roller, said bearing members when the second frame is in normal position maintaining the second roller in pressure engagement with the first roller. 120

SIMON E. SCHROEDER.
